DESIGN FOR A RUG

Wilhelmine von Godin, New York, N. Y.

Application May 4, 1939, Serial No. 84,793

Term of patent 7 years

To all whom it may concern:

Be it known that I, Wilhelmine von Godin, a subject of the German Reich and a resident of the city, county, and State of New York, have invented a new, original, and ornamental Design for Rugs, of which the following is a specification, reference being had to the accompanying drawing, forming part thereof.

The figure is a plan view of a rug, showing my new design.

I claim:

The ornamental design for a rug, as shown.

WILHELMINE VON GODIN.
